ADDRESSING MACHINE

Harmon P. Elliott, Watertown, Mass., assignor
to The Elliott Addressing Machine Company,
a corporation of Massachusetts

Application August 26, 1937, Serial No. 160,985

8 Claims. (Cl. 271—51)

This invention relates to addressing machines of the rotary type and is particularly applicable to those using card stencils. It comprises certain further improvements on apparatus such as 5 shown and described in my Patent No. 1,909,910, dated May 16, 1933, and certain modifications thereof shown in my Patent No. 1,986,800, dated January 8, 1935.

The objects of the present invention include an 10 improved supplemental feeding attachment for use with postal cards of less than standard length, means for ensuring greater certainty of feeding action with cards of any length when being pulled by the frictional action of a revolving drum from 15 the bottom of a stack thereof held in a magazine, (which said means are not herein claimed but are shown, described and claimed in my divisional application S. N. 182,508, filed Dec. 30, 1937) and a modification in the form of the platen sector 20 shown in said patents designed to facilitate the feeding of cards, envelopes or letter sheets by hand individually to the printing zone from one side of the machine, instead of from a magazine located at one end thereof, such as hereinbefore referred to.

The best form of apparatus embodying my invention at present known to me is illustrated in the accompanying three sheets of drawings, in which—

30 Fig. 1 is a side elevation, with parts broken away and others shown in section on line 1—1 of Fig. 2 except the card feeding drum;

Fig. 2 is a partial plan view of a portion of the apparatus with certain superposed parts 35 omitted while others are broken away or shown in section;

Fig. 3 is a detail vertical section on a larger scale like Fig. 1 taken on line 1—1 of Fig. 2, parts being broken away;

40 Fig. 4 is a fragmentary perspective view on an enlarged scale looking in the general direction of the arrow 4 in Fig. 1;

Fig. 5 is a fragmentary cross section on line 5—5 of Fig. 3, the card feeding drum being shown 45 in elevation;

Fig. 6 is a detail true vertical section on an enlarged scale taken on line 1—1 of Fig. 2 and

Fig. 7 is a fragmentary cross section on line 7—7 of Fig. 1.

50 Fig. 8 is a fragmentary vertical section on line 8—8 of Fig. 5.

Throughout the drawings like reference characters indicate like parts. 1 indicates the main frame which is shown as provided with legs so 55 that it may be supported on any convenient table

or other horizontal surface, and the basic construction is similar to that shown in my prior patents hereinbefore referred to, 2 being a revolute ink-carrying sector, 3 a cooperating revolute platen sector or "anvil", these two being 5 geared together as indicated at 4 in Figs. 1 and 7 so as to be revolved in opposite directions by any convenient driving mechanism such as a belt or sprocket chain indicated at 5. Sector 2 is mounted on shaft 6 journaled in fixed bearing 37 10 shown in Fig. 7, and 3 is carried on shaft 13 journaled in rocker frame 7 pivoted at 14 and normally biased by yielding means not shown so as to press sector 3 upward toward the cooperating surface of sector 2. Any convenient ink 15 supplying and distributing mechanism is indicated at 8, and 9 (Fig. 1) is a magazine for a stack of stencils, one of which is indicated at 10 in Figs. 1 and 7. The bottom stencil in such stack is fed out of the magazine between printing 20 operations by a reciprocating hook indicated at 11 and into the oppositely grooved guides 12, 12, which extend through the printing zone between sectors 2 and 3.

The magazine for postal cards or similar articles which are to be printed is indicated at 16 25 in which part of a stack of such cards 17 is shown with the rear edge of the bottom one supported on the flange 18, while its front edge rests upon a revolute drum generally indicated at 19, which 30 is revolved in the same direction as sector 3 by any convenient driving connection such as a belt or sprocket chain indicated at 33 in Fig. 1. Said drum is provided with the usual serrated friction strips of rubber 20, 20, extending along an arc of 35 its periphery on either side of the medial circumferential bearing surface 21, the length of said strips being about equal to that of a standard postal card. The usual pressure roller 22, cooperating with the drum, is journaled in cradle 23 40 by means of shaft 24, said cradle being supported and pressed downwardly by spring 25 carried by the front wall of magazine 16 which also supports the gate 30, adjustable so as to permit only one card at a time to be fed under it by the corrugated rubber strips 20, 20, on drum 19. After 45 the forward edge of such card has passed through the gripping zone between said roller 22 and the raised section 21 of the drum surface it is stripped from the latter by the lip 27 mounted on the adjacent edge of table 26. Superposed spring pressure plate 28 carried by pin 34 mounted in cradle 23 is biased to press downwardly on the upper surface of such card while passing over table section 26 so as to act as a friction drag pre- 50 55

venting said card from being shot too far forward by the feeding mechanism previously described. 29, 29 are side guides for card 17 and 31 is any suitable form of ejector mechanism engaging it 5 after it has passed through the printing zone to positively project it under the downward deflector 32 so as to ensure its dropping into any convenient receptacle (not shown) located beneath such deflector. The table 26 is cut away, as indicated at 36, to leave an open space in which such 10 card feeding mechanism may operate. Guide strips 39, 39 overhang the card edges.

The apparatus so far described conforms generally to the construction shown in my previously 15 mentioned Patent Nos. 1,909,910 and 1,986,800. Drum 19 rotates continuously but exerts sufficient frictional drag on the bottom card to move it out of the magazine only while strips 20, 20 are moving under it. During the rest of each cycle of 20 operations the bottom card rests on the smooth surface of the drum surface section 21, which will not move it.

The first one of the features of novelty in the present invention comprises a supplemental card 25 feeding mechanism designed to cooperate with cards of less than standard length, after the same are no longer being urged forward by the friction strips 20, 20, to ensure the front edge portion of such shorter cards having entered the gripping 30 zone between sectors 2 and 3 before their further progress is checked by the friction drag 28. Such supplemental feeding mechanism is a substitute for either of those shown in my before mentioned Patent No. 1,986,800 and comprises a finger generally indicated at 40 which is pivoted at 41 on drum 19 at a proper point within the periphery thereof so that its free end may project beyond said periphery and engage the rear edge of any postal card after it has passed beyond the zone 40 of any gripping action between drum 19 and roller 22. As shown, pivot 41 is carried by housing 42 detachably fastened to the inner surface of the drum periphery by thumb screw 43 and held in proper position thereon by registry pin 44. Normally said finger is held against a stop 45 on said housing by a tension spring 46 which is anchored on the drum at 41 and connected to said finger by having its other end engage slot 48 therein. The housing and main portion of the finger are located in the interior of the drum periphery within the plane in which the adjacent edge thereof lies so as to clear any portions of the main frame of the machine during revolution 50 of the drum, the free end of the finger being laterally offset along the line of the drum axis so as to project outwardly close to one edge of said periphery through the open space 36 in table 26, as best shown in Fig. 5.

As indicated in Fig. 1 said finger mechanism 60 is normally biased so as to have such projecting end inclined forwardly at an angle to any drum radius passing through its pivot, thus causing it to slightly overhang the rear edge of the card and prevent the same from bending or lifting upward 65 and so freeing itself from such engagement. Said engagement continues until and slightly after said finger strikes the edge of the stripper 27, after which the spring 46 yields sufficiently to permit the finger to rotate on its pivot 41 in a counterclockwise direction looking at Fig. 1 sufficiently to slip under said stripper edge. By that 70 time, however, the short postal card has been advanced to a position such that its forward edge is well within the gripping zone of sectors 2 and 75 3 and it is thereby fed onward through the print-

ing zone and delivered into the control of the ejector 31. Similarly the yielding action of spring 46 permits the finger to slip under and turn slightly about the lower edge of magazine gate 30 without causing stoppage or breakage of 5 the apparatus. A second novel feature is the notch 35 in ring shaped ridge 21. Since the friction of rubber strips 20, 20 on the bottom card 17 which acts to drag it out of magazine 16 and advance its forward end into the roll pass between the ring-shaped ridge 21 on the drum surface and the pressure roll 22 is in part a function of the downward pressure produced by the weight of that card and that of the stack of cards above it, such feeding action becomes less efficient when 10 there are only a few cards left in the magazine, and sometimes a card will stop on making contact with the roller while the drum surface slips along under it. I have found that if the ring 21 be transversely notched as indicated at 35 in 15 Figs. 1 and 8 this occasional difficulty is obviated. Such notch should be located in line with or slightly in the rear of, the forward ends of strips 20, 20 and be of a depth at least about equal 20 to the thickness of a postal card. 25

When such notch has been formed in the ring-shaped drum surface 21 and a card thus stalls with its forward end at the entrance to the roll pass, such notched portion of ring 21 soon slides along under the edge of such card end and the latter then flexes down under pressure of roller 22 into the notch, with the result that the resistance of such roller to its forward movement is removed. Also there then occurs a positive biting 30 action on the card between the rear edge of such 35 notch and the roller which further ensures resumption of the temporarily interrupted feeding action. 35

If the action of the drum feed on all bottom cards in the magazine at all times was exactly 40 uniform, so that the exact point on ring 21 which would then underlie the forward end of each card could be accurately determined, notch 35 should be located there. But that is practically impossible, so I prefer to place it slightly in the 45 rear of the forward ends of rubber strips 20, 20, as shown in Fig. 1, which ensures its being also somewhat in the rear of the front edge of any card being fed by said strips so that the notch may then surely be brought under that edge by 50 continued drum rotation, and function as first above explained—if such card has stalled at the entrance to the roll pass. 55

A third feature of novelty in the machine here shown as an embodiment of my present invention 55 is the particular configuration of the hub of the platen sector 3, as appearing in Figs. 1 and 7.

While postal cards are usually fed to the printing zone from a stack in magazine 16 as previously described it is sometimes desired to 60 insert them individually from one side of the machine as indicated in Fig. 7. Also when addressing envelopes or letter sheets it is preferable, if not necessary, to thus handle them individually, with the machine here shown. 65

Since the stencil guides 12, 12 are necessarily located at a considerable distance above table 2 in order to leave a space below the stencil for free movement of the article to be printed, the hub of the platen sector 3 as heretofore constructed of 70 cylindrical form has projected above the plane of such table when the sectors are in the positions shown in all figures of the drawings,—which, of course, are the ones such sectors occupy, or through which they are moving, at the time of 75

such insertion of the card or sheet into the printing zone. The side surface of such ordinary form of hub would then project up through the opening in the table and be apt to engage the advancing edge of the sheet or card and interfere with its continued movement into proper position between the sectors, and to avoid this I now bevel the periphery of that end of the hub as shown at 15 so that its outer edge lies in or below the plane 10 of the table surface, as indicated in Figs. 1 and 7. The hub surface so produced then slopes upwardly from such outer edge and merges into any full, circular cross section of the remaining portion thereof. Consequently a sheet of paper, card or 15 envelope may then be quickly and easily slid sideways along the table surface up into proper position between the platen sector 3 and the under surface of the stencil 10 before the sectors grip the two together and perform the desired 20 printing.

The mode of operation of the machine as a whole when the various features of the present invention are included therein is believed to have been made clear in the foregoing description so 25 as to require no further explanation.

The advantages resulting from the use of the notched drum and the improved form of platen sector hub are believed to be entirely novel. Those of the particular form of supplemental 30 card feeding attachment here shown over both those shown in my prior patent No. 1,986,800 may be briefly pointed out as follows: The attachment here shown is much simpler and more compact than that shown in Figs. 6 and 7 of 35 said patent and is self-adjusting in correct position whenever placed in position, while the patented form had to be adjusted by the operator every time it was used, and frequently mal-adjusted. Moreover the yielding fingers 1, 1 in 40 that patented form extended radially of the drum at the moment of initial engagement with the rear end of the card, and, if the latter presented too much resistance to their forward urge they tended to swing backward and to slide 45 under said edge instead of functioning properly. This particular difficulty was aggravated in the form shown in Figs. 1, 2, 4 and 5 of said patent because the wire fingers 9 there illustrated were already in backwardly inclined position on initial 50 contact with the card and during the entire period of their operation. As contradistinguished from both said prior constructions the finger 40 of my present invention is yieldingly held in a forwardly inclined position with reference to the card and never swings backwardly 55 beyond a position at right angles to the plane thereof at any time during its feeding action. Consequently, there is no tendency for the card to bend or jump up away from such finger.

60 Various changes in the details of construction shown and described could be made without departing substantially from the principles of operation of my invention and the character of results obtained thereby.

65 Having described my invention, I claim:

1. In an addressing machine comprising a combined card gripping, printing and forwarding mechanism together with a rotating drum and cooperating superposed pressure roller located at the proper distance from said mechanism and adapted to feed the forward end of a card of a predetermined length toward, and part way into, the gripping zone thereof, supplemental feeding means for advancing a shorter card an 75 additional distance toward said printing mecha-

nism sufficient to also project its forward end into such gripping zone, which said supplemental means comprises a device provided with means for clamping it to the inner surface of the periphery of said drum and adapted to engage the rear edge of any such card and to continue such engagement along a portion of said card's path extending beyond the zone of cooperation between said drum and pressure roller. 5

2. An apparatus such as defined in claim 1 in which said attachment is held in operative position by a screw carried by said drum; whereby on loosening such screw such supplemental feeding means may be removed from the apparatus as a unit and the machine left in its original condition adapted to feed cards of standard length in the normal manner. 15

3. An apparatus such as defined in claim 1 in which said attachment comprises the combination of a member projecting in a general direction radial of said drum beyond the periphery thereof into the path of such card, and means for yieldingly holding said finger in proper position for engaging the rear end of any card being fed along such path, but capable of allowing its 20 projecting portion to move rearwardly and inwardly with respect to said periphery whenever such portion comes in contact with any immovable element of the machinery. 25

4. An apparatus such as defined in claim 1 in which said attachment comprises the combination of a finger pivoted to said drum at a point within the periphery thereof so as to have one end projecting beyond said periphery, together with a spring anchored to said drum at another 35 point within its periphery and connected to said finger at a point thereon between said pivot and the axis of the drum. 30

5. An apparatus such as defined in claim 1 in which said attachment comprises the combination of a finger pivoted to said drum at a point within the periphery thereof so as to have one end projecting beyond said periphery, together with a spring anchored to said drum at another 40 point within its periphery and connected to said finger at a point thereon between said pivot and the axis of the drum and a stop on said drum against which said finger is normally held by 45 said spring.

6. In a rotary printing apparatus in which 50 cards to be printed are fed into guides by a revoluble drum having a friction-producing surface portion extending along an arc of its periphery and a pressure roller cooperating with another portion of such drum surface in feeding 55 such card, the combination of a finger pivotally supported by said drum at a point within its periphery adjacent the rear end of said friction-producing surface with one end capable of projecting beyond said periphery, a stop on said 60 drum for said finger so located that when engaged by the latter its projecting portion will engage the rear end of any card which has just passed the point at which any gripping action of said drum and pressure roller ceases, and 65 yielding means tending to hold said finger against said stop.

7. An apparatus such as defined in claim 6 in which said pivot, spring and one end portion of said finger are located near one edge of the 70 periphery of said drum but inside of the plane in which said edge lies, while the free end portion of said finger is offset laterally so as to project beyond said periphery edge into the path of such card and is inclined forwardly at an 75

angle to any drum radius passing through said pivot; whereby its free end will slightly overhang the rear edge of such card when and after initially engaging the same, thereby tending to prevent said card edge from moving away from said drum periphery and out of such engagement.

8. In an apparatus of the class described including a rotating drum for feeding a card along

a path tangent to its periphery, the combination of a finger pivoted on such drum and having its free end projecting beyond the periphery thereof in a forwardly inclined position so as to overhang the rear end portion of such card, together with means which yieldingly hold said finger in such position, but permit it to swing backward whenever it strikes an immovable obstruction.

HARMON P. ELLIOTT.
